UNITED STATES PATENT OFFICE.

RAPHAEL S. GREEN, OF CHICAGO, ILLINOIS.

SHARPENING-MACHINE.

1,143,383.

Specification of Letters Patent. Patented June 15, 1915.

Application filed August 21, 1914. Serial No. 367,892.

To all whom it may concern.

Be it known that I, RAPHAEL S. GREEN, a citizen of the United States, residing at Chicago, in the county of Cook and State 5 of Illinois, have invented certain new and useful Improvements in Sharpening-Machines, of which the following is a description, reference being had to the accompanying drawings, forming a part of this specification, in which corresponding numerals of reference in the different figures indicate like parts.

The object of my invention is to provide a grinding machine for sharpening razor 15 and other blades, which machine shall be so constructed as to automatically hone and strop the blades with uniformity, accuracy, and speed.

To these ends, my invention consists in 20 the combination of elements hereinafter more particularly described and definitely pointed out in the claims.

In the drawings Figure 1. is a front elevation of a device embodying the features 25 of my invention. Fig. 2. is a plan view thereof, Fig. 3. is a right-hand end elevation, Fig. 4. is an enlarged vertical sectional view in detail, taken upon the line 4—4, Fig. 2, viewed in the direction of the arrow 30 there shown, Fig. 5. is a vertical sectional view taken upon the line 5—5, Fig. 2, viewed in the direction of the arrow there shown, Fig. 6. is a plan view of a blade-holder and Fig. 7. is a side view thereof.

Referring to the drawings, 1 represents a base-plate or foot support, formed from cast metal to which are bolted upright rear frame members 2, 2, and front frame members 3, 3, at opposite ends of the machine, 35 the uprights 2, and 3, at the respective ends being connected by means of a horizontal frame member 4. Supported in bearings in the uprights 2, 2, is a horizontal shaft 5, having a driving pulley 6, upon its outer 40 end. Extending rearwardly from the supports 2, and integral therewith, are arms or extensions 7, 7, to which counterpart bearing members 8, 8, are jointedly connected by means of bolts 9, 9. Said bearing members 45 are extended forwardly in the vertical planes respectively of the uprights 2, said supports and the upper portions of said uprights being normally held in predetermined relation to each other by means of bolts 10, 10, the heads of which are secured to the parts 7, the pulleys being extended 50 upwardly, through bores in the parts 8, and provided with adjusting thumb-nuts 11, upon their upper ends. Coiled springs 12, Fig. 3, are interposed in suitable recesses 55 between the meeting faces of the parts 7, and 8, which springs tend to lift the forward ends of the parts 8. The thumb-nuts 11, enable said parts to be adjusted to any desired position for the purpose hereinafter 60 stated. Upon removing said nuts, the parts 8, may be thrown back upon their hinges to substantially vertical positions, the extent of the movement being limited by means of opposing lugs 13, and 14, upon the parts 7, 70 and 8, respectively, Figs. 3 and 5, which are arranged to contact with each other to form limiting stops. The bearing supports 8, 8, are rigidly connected together by means of a horizontal t.-rod 15, Figs. 2, 3 and 5, 70 said rod being provided with end nuts 16, 16. Journalized in the forward ends of the parts 8, 8, is a shaft 17, having a driving pulley 18, upon its left-hand end. The shafts 5, and 17, are arranged in parallel 75 relation and each is a substantial counterpart of the other, and intended as a support for a revoluble drum having upon its surface different zones comprising or provided with abrading or sharpening material varying in character. The abrading or sharpening material of the different zones may be secured in place in any approved way. In the example illustrated, I have shown drums or rollers 19, 20, which will be referred to generally hereafter as the upper 80 and lower rollers respectively. Upon the right hand end of each of said rollers is secured a ring or zone 21, of stone, carbonundum, or other suitable abrading material, 85 while in the adjacent zone to the left thereof, I prefer to provide a composition or cloth,—22, of fine emery. The next adjacent zone 23, to the left, I prefer to form of metal or metallic alloy such, for example 90 as aluminum, Babbitt-metal or other analogous material having ductile characteristics. The remaining parts 24, of the drums are provided with a covering of leather of a fineness and quality best adapted for honing 95 purposes.

The pulleys 6 and 18 are intended to be driven by separate belts, from any suitable source of power, not shown, at corresponding rates of speed and in opposite directions 100 so as to actuate the rollers 19 and 20, in the manner indicated by the arrows shown in

Fig. 5. The peripheral surfaces of the rollers are intended to be separated from each other as more clearly shown in the Fig. 5, the degree of separation being governed by means of the adjusting nuts 11.

Formed upon the front and rear respectively of the upright members 3, 3, are flanges 25, 26, Figs. 1, 4 and 5, which extend downwardly from the top and are 10 adapted to form vertical guides for counterpart bearing blocks 27, 28, better shown in Figs. 2 and 4, which blocks have depending portions 29, 30, Fig. 4, which are fitted side by side between the flanges 25 and 26. Said 15 parts 29, and 30, have opposing faces which are cut away as shown at 31, and 32, to permit the insertion of a fastening bolt 33, having a tightening nut 34, Figs. 1 and 2, upon its outer end. The head of said bolt 20 is arranged to overlap the parts 29 and 30, as shown in Fig. 4, so that when the bearing blocks 29, and 30, are properly adjusted as to height, they may be rigidly secured in place by tightening said nuts. Each of the 25 parts 29 upon the bearing block 27, is made longer than the adjacent part 30, and is provided with a rearward extension 35 arranged to project beneath the part 30. A pin 36, is formed upon the part 35 and arranged to extend into an eccentric groove 37, formed in a movable eccentric member 38, rigidly attached to a pivot-pin 39, extended through the part 3, there being two of said eccentric members, one located upon 30 the inner face of each of the upright members 3. Upon the outer end of each of the pins 39 is rigidly attached an adjusting arm 40, having an adjusting pin 41, which is loosely passed through a bore therein and 35 adapted to enter any one of a series of bores 42, Figs. 3 and 4, formed in the faces of the uprights 3, 3, respectively. A feed-screw 43, has its ends journaled in the blocks 28, 28, and is provided with a driving pulley 44, adapted to be driven from any approved 40 source of power. Journaled in bearings in the blocks 27, 27, is a shaft, the end or bearing portions of which are designated by 45, 45. A portion, 46, of said shaft is eccentric 45 to the parts 45, for the purpose hereinafter stated. Said shaft is generally referred to as the eccentric shaft and is adapted to be driven at a uniform rate of speed by means 50 of a pulley 47.

55 The feed and eccentric shafts 43, and 46, respectively, are adapted to feed and manipulate a work-holder generally designated by 48, shown in all of the figures except 4. The work-holder is composed of several elements 60 comprising a main body 49, having a rear extension 50, which is integral therewith. Jointedly connected to the rear end thereof by means of a bolt 51, is a counterpart member 52, the forward end of which is detachably connected to the main member by

means of a catch or button 53, rigidly attached to the lower end of a pin 54, which is journaled in a bore formed in the part 49, and is provided with an operating arm 55, rigidly attached to the upper end. The 70 members 50, and 52, are arranged parallel to each other with a space or opening between as clearly shown in Figs. 5 and 7, the rear portion of said opening as shown in Fig. 5, being intended for the reception 75 of the eccentric shaft 46, the diameter of which corresponds to the distance between the opposing faces above and below which contact therewith, while in the forward part are fitted counterpart blocks 56 and 57 respectively, the former being attached to the part 50, and the latter to the part 52. Said blocks have counterpart semi-circular notches 58, which are threaded as indicated in dotted lines in Fig. 6, and when brought 80 together constitute a two-part nut adapted to receive the feed-screw 43. A screw threaded stem 59, is tapped into the forward end of the part 49, and secured in place by means of a lock-nut 60. Rigidly attached to 85 the forward end of the part 59, is a flat spring 61, to the forward end of which are secured opposing clamping members 62, 62, adjustably connected by means of a bolt 63, and thumb-nut 64. Formed upon or riveted 90 to the forward ends of said clamping members are jaws 65, 65, adapted to grasp and hold a razor or other blade 66, in position to contact with the sharpening rolls.

The feed-screw 43, is provided with blank 100 spaces 67, and 68 respectively at opposite ends for the purpose hereinafter stated, while the eccentric shaft has the non-eccentric parts 45, 45, above referred to, made to correspond in relative length and position to 105 the non-threaded portions respectively, of the feed shaft, it being understood that the threaded portion of the feed shaft and the eccentric 46, are arranged to correspond with each other.

110 The operation is as follows: The blade 66, having been clamped in the work-holder as shown in Figs. 6, and 7, the part 52, is released by turning the catch 53 to permit said part to assume the position indicated in dotted lines in Fig. 7. The holder is then placed in position at the right hand end of the machine with the blocks 56, and 57, encircling the blank part 67, of the feed shaft, it being assumed that the grinding 115 rolls, and the feed and eccentric shafts are in continuous operation. The part 52, is then lifted and locked in its normal position by means of the catch 53. The holder is then moved laterally until the two-part 120 nut is in engagement with the feed-screw and the rear portion of the holder in engagement with the eccentric 46. This adjustment is intended to be such as to cause the left-hand edge of the blade to begin its 125 130

contact with the right-hand end of the grinding stones 21. The work holder 48, is then fed laterally toward the left by the continuously rotating feed-screw 43, until it reaches the blank spaces 68, and 45, respectively of the feed and eccentric shafts, at which time the adjustment should be such as that the right hand edge of the blade will have reached or passed off from the left-hand ends of the sharpening drums. During the time the work holder is in engagement with the feed screw, and is being moved laterally thereby the rotation of the eccentric shaft will cause the eccentric to vibrate the rear end of the work-holder with the feed shaft as a pivot therefor, so as to bring the blade 66, into alternate contact with the upper and lower sharpening rollers. It will thus be seen that the blade has its opposite sides alternately brought into contact with the successive abrading, smoothing and honing surfaces which are so apportioned respectively as to leave it in a finished condition when the holder attains its limit of travel. The holder is then removed and the operation repeated with a new blade. Two or more work-holders may be utilized at once, the number limited only by the length of the sharpening rollers and the relative length of the blades to be sharpened.

It is obvious in order to produce the corresponding angles upon opposite sides of the blade, that the feed shaft which forms the pivot of the work holder, should be in a horizontal plane midway between the upper and lower sharpening rollers. The latter having been adjusted by means of the thumb-nuts 11, so as to form a predetermined space between the rollers, the nuts of the clamping bolts 33 are loosened and the handles 40, are actuated, thereby causing the eccentrics 38, to act upon the pins 36, and thus raise or lower the blocks 27, until the axis of the shaft 45, is in the horizontal plane midway between the sharpening rollers. The locking pins 41, are then placed in the proper holes, the bearing blocks 28 are then adjusted to bring the axis of the feed-shaft 43, in the same plane when the nuts upon the bolts 33, are tightened, thereby clamping the blocks 27 and 28 rigidly in place.

The extent of eccentricity of the eccentric shaft should be such as to cause the blade 66, to be alternately pressed against the sharpening rollers; and in order to overcome the positive action of the eccentric and to insure the desired degree of pressure between the blade and grinding surface, the spring 61, is interposed.

I do not wish to be limited to the exact construction shown, inasmuch as it may be varied without departing from the spirit of the invention.

Having thus described my invention, I claim:

1. A machine of the class described, comprising in combination two rollers having parallel axes, said rollers having a succession of zones corresponding in relative position respectively formed from material for grinding and honing an article to be sharpened, means for rotating said rollers on opposite directions, a feed-screw arranged parallel to the axes of said rollers, a work-holder pivotally mounted thereon for holding an article to be sharpened, an eccentric shaft arranged parallel to said feed-screw, the eccentric portion of said shaft corresponding substantially in length to the threaded portion of said feed-screw, and in operative connection with said work-holder, to cause the vibration of the latter and means for simultaneously rotating said feed-screw and eccentric shaft.

2. A sharpening machine comprising in combination two parallel rollers said rollers having peripheral surfaces of abrading and honing material arranged in successive order thereon, means for rotating said rollers in opposite directions, a feed-screw arranged parallel to the axes of said rollers and in a plane midway between them and at right angles to the plane of the axes of said roller a work-holder threaded upon said feed-screw, said screw forming a pivot therefor, an eccentric shaft arranged parallel to said feed-screw, the axis of said shaft being in the same plane with the axis of said feed-screw and in vibratory connection with said work-holder and means for rotating said feed screw and eccentric shaft.

3. A sharpening machine comprising in combination two parallel rollers, having peripheral surfaces for honing and stropping purposes, means for rotating said rollers in opposite directions, a feed-screw arranged parallel to the axes of said rollers, an eccentric shaft arranged parallel to the axis of said feed-screw, means for rotating said feed-screw and eccentric shaft respectively, a work-holder threaded upon said feed-screw, said holder being in operative connection with said eccentric shaft and adjustable means for bringing the axes of said feed-screw and eccentric shaft in a common plane midway between the axes of said rollers and at right angles to the plane of said axes.

4. A sharpening-machine, comprising, in combination, two parallel sharpening rollers having honing and stropping surfaces, means for rotating said rollers in opposite directions, a feed-screw arranged parallel to the axes of said rollers and in a plane midway between them, the threaded portion of said screw exceeding in length that of said rollers, and extending beyond one end thereof to permit a work-holder to be

threaded thereon without bringing the work into contact with said rollers at the outset, a work-holder threaded upon said feed-screw, said screw forming a pivot therefor, 5 an eccentric shaft arranged parallel to said feed-screw, the axis of said shaft being in the same plane with that of said feed-screw and in vibratory connection with said work-holder, and means for rotating said feed-screw and shaft.

5. A sharpening-machine, comprising, in combination, two parallel rollers having honing and stropping surfaces, means for rotating said rollers in opposite directions, a 15 feed-screw arranged parallel to the axes of said rollers, an eccentric-shaft arranged parallel to the axis of said feed-screw, the length of the eccentric portion thereof being

less than that of said feed-screw, to permit a work-holder to be placed thereon and removed therefrom while the machine is in operation without causing a vibration of said holder until the latter is in place, means for rotating said feed-screw and eccentric-shaft respectively, and a work-holder threaded upon said feed-screw, said holder being in operative connection with said threaded shaft. 20

In testimony whereof, I have signed this specification in the presence of two subscribing witnesses, this 11th day of August, 1914. 25

RAPHAEL S. GREEN.

Witnesses:
